[57] CLAIM

The ornamental design for a bike seat bag, as shown.

DESCRIPTION

FIG. 1 is a side perspective view of a bike seat bag showing my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right end elevational view thereof; and,

FIG. 7 is a left end elevational view thereof.

The partially shown cross line shading shown on the surfaces is intended to represent a conventional fabric and is understood to cover the surfaces indicated.

FIG. 1

FIG. 2

FIG. 3

FIG. 4

FIG. 5

FIG. 6

FIG. 7
